Primary Examiner — Melanie H Tung*Assistant Examiner* — Darmawan Truong(74) *Attorney, Agent, or Firm* — Fish & Richardson P.C.(57) **CLAIM**

The ornamental design for a display panel portion with an animated icon, substantially as shown and described.

DESCRIPTION

FIG. 1 is a first image in a sequence for a display panel portion with an animated icon, showing our new design.

FIG. 2 is a second image in the sequence thereof.

FIG. 3 is a third image in the sequence thereof.

FIG. 4 is a fourth image in the sequence thereof.

FIG. 5 is a fifth image in the sequence thereof.

FIG. 6 is a sixth image in the sequence thereof, and,

FIG. 7 is a seventh image in the sequence thereof.

The appearance of the transitional image sequentially transitions between the images shown in FIGS. 1-7.

The process or period in which one image transitions to another forms no part of the claimed design.

The broken lines showing a display panel portion forms no part of the claimed design. The remaining broken lines showing portions of the animated icon in FIGS. 1-7 form no part of the claimed design.
